UNITED STATES PATENT OFFICE.

ARTHUR McKEVES PARKER, OF GEORGETOWN, SOUTH CAROLINA.

MACHINE FOR MAKING COIL-SPRINGS.

1,327,728.

Specification of Letters Patent.

Patented Jan. 13, 1920.

Application filed June 12, 1919. Serial No. 303,573.

To all whom it may concern:

Be it known that I, ARTHUR McK. PARKER, a citizen of the United States, and a resident of Georgetown, in the county of 5 Georgetown and State of South Carolina, have invented certain new and useful Improvements in Machines for Making Coil-Springs, of which the following is a specification.

10 My invention is an improvement in machines for making coil springs, and has for its object to provide a simple, easily operated machine of the character specified by means of which springs of any desired diameter may be coiled, and with the coils at various distances apart.

In the drawings:

Figure 1 is a front view of the improved machine;

20 Fig. 2 is a side view.

In the present embodiment of the invention, a suitable supporting frame is provided, consisting of a base 1 and upright plates 2 and 3 which are substantially parallel and spaced apart from each other, and the base may be secured to a fixed support 4 by means of screws 5 or the like.

A lever 6 is pivoted to the outer face of the plate 3 by means of a bolt and nut 7, 30 a coil spring 8 being arranged between the head of the bolt and the lever for normally pressing the lever toward the plate. The plate 3 is extended below the base, as shown in Fig. 2, and this extended portion has an 35 arc shaped slot 9 which is formed on an arc whose center is the bolt 7.

A bolt 10 is passed through this slot from the rear forwardly, and through a registering opening in the lower end of the lever 6, 40 the head of the bolt being behind the extension of the plate. A wing nut 11 engages the bolt outside of the lever, and it will be evident that by turning the wing nut in the proper direction the lever may be clamped 45 to the plate.

The plates 2 and 3 have registering series 50 of openings 12 of different size, the openings ranging from large to small, and the pairs of registering openings are designed to receive interchangeable crank shafts 13, each of which is provided at one end with a crank 14 and at the other with a diametrical opening 15 for receiving one end of the wire 16 from which the spring is 55 formed. The wire is tensioned during the turning of the same upon the crank shaft

or spindle by means of a diametrical slot 17 in the head 18 of a screw bolt 19 which is engaged with an arc shaped slot 20 in the plate 3 above the series of openings 12. 60

This set screw is engaged by a handled nut 21 on the rear face of the plate, and it will be obvious that by means of the handle the slot in the head of the bolt may be set at any angle with respect to the spindle 65 12 with which it is being used.

Referring to Fig. 1, it will be noticed that the diametrical slot is beveled or flared in both directions. That portion of the plate 3 above the slots 12 is reduced, the front 70 face of the plate being cut away, as shown. The lever 6 at the end adjacent to the openings 12 is beveled to form an inclined edge 22, and this is the laying edge for insuring the proper spacing of the coils of the 75 spring during the winding thereof. The end of the lever having the bevel 22 is adjusted toward and from the plate 3 by means of a set screw 23 which is threaded through the lever into engagement with the face of 80 the plate.

It will be understood that the lever 6 is set with that end 22 of the lever 6 adjacent to the spindle upon which the spring is being wound so that the beveled laying edge 85 of the lever will move in contact with the spindle. The set screw 19 serves as a guide for guiding the wire to the proper place on the spindle, this set screw being placed in that portion of the slot 20 which is nearest 90 to the spindle in use. In small wire a bar 24 is used. This bar is pivoted at one end on the set screw 7 and the other end is adjacent to the openings 12. The free end of the bar 24 will engage the wire as it winds 95 on the spindle and will hold it close against the face of the plate 3 as shown in Fig. 2, while the lever 6 will lay the wire properly on the spindle.

In operation, the wire from which the 100 spring is to be formed is engaged with the opening 15 of that spindle corresponding to the diameter of the coil to be formed, this spindle being inserted in the proper pair of openings 12. The body of the wire is 105 engaged with the slot 17 of the bolt 19. The lever 6 or 24, as the case may be, is adjusted to properly lay the coils upon the spindle, and the spindle is rotated. The slot 17 is a tensioning device, and it will 110 be evident that as the spindle is rotated the wire will be drawn upon the spindle and

will be tightly wound thereon, and the coils will be properly spaced.

The pitch of the coil of the spring is controlled by the longitudinal movement of the spindle 13, by the levers 6 and 24. The lever 24 holds the wire close against the plate 3, while the lever 6 determines the pitch of the coil, being adjustable toward and from the lever 24, for this purpose.

10 When the wire is engaged with the end of the spindle and the spindle is turned with the levers 6 and 24 properly adjusted, the wire will be laid upon the spindle in coils equally spaced apart from each other by the levers 6 and 24, and the formation of these coils will feed the spindle longitudinally.

It will be noticed, referring to Fig. 2, that the end of the setscrew 23 which engages the plate 3 is tapered, as indicated at 20 26, and the bar 24 has a tapering opening through which the tapering portion extends into engagement with the plate 3.

I claim:

25 1. A device of the character specified comprising a suitable support having up-standing laterally spaced plates, a lever pivoted intermediate its ends to swing on the outer face of one of the plates, said plates 30 having arc shaped series of registering openings concentric with the pivotal connection of the lever, that plate carrying the lever having an arc shaped slot above the series and an arc shaped slot at the lower 35 end of the plate, said openings being of varying diameter and being adapted to receive wire winding spindles of various size, the upper end of the lever being beveled to form a laying surface for the wire, means 40 engaged with the upper arc shaped slot for tensioning the wire and adjustable in the slot, and means engaged with the lower slot and connected with the lever for holding said lever in adjusted position, said lever 45 being mounted to yield away from the plate at its pivotal connection for the purpose specified, the tensioning means comprising a bolt passing through the slot and having its head at the front thereof, the head of the 50 bolt having a diametrical slot for the wire, and a handled nut engaging the bolt on the opposite side of the plate.

2. A device of the character specified comprising a suitable support having laterally spaced plates, a lever pivoted intermediate its ends to swing on the outer face of one of the plates, said plates having arc shaped series of registered openings concentric with the pivotal connection of the lever, that plate carrying the lever having an arc 60 shaped slot above the series and an arc

shaped slot at the lower end of the plate, said openings being of varying diameter, and being adapted to receive wire winding spindles of various size, the upper end of the lever being beveled to form a laying surface for the wire, means engaged with the upper arc shaped slot for tensioning the wire and adjustable in the slot, and means engaged with the lower slot and connected with the lever for holding said lever in adjusted position, said lever being mounted to yield away from the plate at its pivotal connection, for the purpose specified.

3. A device of the character specified comprising a suitable support having up-standing laterally spaced plates, a lever pivoted intermediate its ends to swing on the outer face of one of the plates, said plates having arc shaped series of registering openings concentric with the pivotal connection of the lever, that plate carrying the lever having an arc shaped slot above the series and an arc shaped slot at the lower end of the plate, said openings being of varying diameter and being adapted to receive wire winding spindles of various size, the upper end of the lever being beveled to form a laying surface for the wire, means engaged with the upper arc shaped slot for tensioning the wire and adjustable in the slot, and means engaged with the lower slot and connected with the lever for holding said lever in adjusted position.

4. A device of the character specified, comprising a suitable supporting plate having a series of means for engagement by wire winding spindles of various size, a bar for pressing the wire into contact with the plate as it is wound on the spindle, a lever for laying the coils on the spindle, said lever being normally spring pressed intermediate its ends toward the support, means for holding the end of the lever remote from the spindle to the plate, and means in connection with the lever and engaging the plate for pressing the operative end of the said lever away from the bar.

5. A device of the character specified, comprising a supporting plate having means for supporting a wire winding spindle for rotation, means for holding the wire in contact with the face of the plate during the winding thereof on the spindle, said spindle being movable longitudinally through the holding means, and means co-operating with the holding means and adjustable with respect thereto for determining the pitch of the coil of the spring, said means engaging the spindle between the coil and the plate.

ARTHUR McKEEVES PARKER.
